UNITED STATES PATENT OFFICE.

ALFRED JOHN MEAKIN, OF STOKE-UPON-TRENT, ENGLAND, ASSIGNOR TO HUGH C. EDMISTON, OF NEW YORK, N. Y.

DESIGN FOR A COVERED DISH.

SPECIFICATION forming part of Design No. 36,467, dated July 28, 1903.

Application filed June 18, 1903. Serial No. 162,142. Term of patent 3½ years.

To all whom it may concern:

Be it known that I, ALFRED JOHN MEAKIN, a citizen of Great Britain, and a resident of Wolstanton, Stoke-upon-Trent, in the county of Stafford, England, have invented a new, original, and ornamental Design for a Covered Dish; and I do declare the following to be a full, clear, and exact description of the same, reference being had to the accompanying drawings, forming part thereof.

In the drawings, Figure 1 is a perspective view of a covered dish embodying my design, and Fig. 2 is a top plan view of the same.

All the ornamentation is embossed on the surface of the ware, but not deeply.

What I claim is—

The ornamental design for a covered dish, as shown.

ALFRED JOHN MEAKIN.
